Specification for Design.

Patented May 18, 1915.

Application filed February 12, 1915. Serial No. 7,885. Term of patent 7 years.

To all whom it may concern:

Be it known that I, GEORGE C. LUNT, a citizen of the United States of America, and residing at Greenfield, in the county of Franklin and State of Massachusetts, have invented a new, original, and ornamental Design for a Handle for Spoons, Forks, or Similar Articles, of which the following is a specification, reference being had to the accompanying drawing, forming a part thereof, in which—

Figure 1 is a front view of a spoon showing a handle embodying my design, and Fig. 2 is a rear or back view of the same.

I claim:

The ornamental design for a handle for spoons, forks, or similar articles, as shown.

GEORGE C. LUNT.
